PILLOW

Bertha Godfrey, New York, N. Y.

Application June 27, 1951, Serial No. 15,683

Term of patent 7 years

(Cl. D3—9)

To all whom it may concern:

Be it known that I, Bertha Godfrey, a citizen of the United States of America, resident of city, county, and State of New York, have invented a new, original, and ornamental Design for Pillow, of which the following is a specification, reference being had to the accompanying drawing, forming a part thereof.

In the drawing:

Fig. 1 is a perspective view of a pillow, showing my new design;

Fig. 2 is a rear elevation of the pillow shown in Fig. 1.

I claim:

The ornamental design for a pillow, as shown.
BERTHA GODFREY.
